UNITED STATES PATENT OFFICE.

STEPHEN S. GRADY, OF NEWTONVILLE, MASSACHUSETTS, ASSIGNOR TO JAY K. COHEN
AND SAMUEL K. COHEN, BOTH OF NEW YORK, N. Y.

SHORT-CIRCUIT-PROOF SOCKET.

Application filed December 13, 1921. Serial No. 522,011.

To all whom it may concern:

Be it known that I, STEPHEN S. GRADY, a citizen of the United States, residing at Newtonville, county of Middlesex, and State 5 of Massachusetts, have made certain new and useful Improvements in Short-Circuit-Proof Sockets, of which the following is a specification, taken in connection with the accompanying drawings.

10 My invention relates to electric light sockets and more particularly to a pull socket which is short circuit proof; that is, the current cannot be short circuited within the lamp socket.

15 My invention further relates to such a pull socket which, should any foreign substance work into the switch mechanism, will give visible notice that it is out of order. Instead of short circuiting, the lamp will 20 light.

25 My invention further relates to a pull socket switch, which is made of the minimum number of parts. My invention further relates to a ratchet which is operated directly by the axle or arbor. My invention further relates to an axle or arbor provided with an integral pawl or pin, and also preferably with a chain holder. My axle 30 is preferably, though not necessarily, struck up from sheet metal.

35 My invention further relates to the spring of the switch being automatically put under tension when the two insulating members or porcelains are brought together. My invention further relates to the eyelet or horn and also to means carried by the chain which assists in holding the horn or eyelet in position after the pull socket has been partly assembled or partly dismantled.

40 My invention further relates to a pull socket having either a double break, or a semi-double break, or a single break switch.

45 My invention further relates to certain details of construction, articles of manufacture, and combinations which will be more fully described in the specification and pointed out in the claims.

50 In the accompanying drawings the same reference numerals refer to similar parts in the several figures.

Fig. 1 is a vertical section through my pull socket;

Fig. 2 is a horizontal section substantially on the line 2—2 of Fig. 1;

Fig. 3 is a perspective view of the insulating switch cam with the ratchet; 55

Fig. 4 is a perspective view of the same insulating switch cam, but viewed from the opposite side from that shown in Fig. 3;

Fig. 5 is a blank from which I preferably 60 strike up my axle or arbor;

Fig. 6 is a perspective view of the axle or arbor formed from the blank shown in Fig. 5;

Fig. 7 is a vertical section through the 65 porcelains and a portion of the screw shell contact;

Fig. 8 is a detail view, partly in side elevation and partly in section, showing the manner of bringing together the two porcelains and thereby automatically placing 70 the spring under tension;

Fig. 9 is a detail fragmentary view of a modification showing a switch provided 75 with a semi-double break;

Fig. 10 is a detail fragmentary vertical section showing another modified form of a switch provided with a single break;

Fig. 11 is a detail vertical section of a modification in which a one piece porcelain, 80 or other insulating member, is used;

Fig. 12 is a side elevation of the one-piece porcelain shown in Fig. 11.

In the illustrative embodiments of my invention shown in the drawings, 1 is a pull- 85 socket, having the ordinary metallic cap 2, metallic shell 3, screw-shell contact 4 and fiber or other insulating members 5 and 6, all of which form no part of my invention.

I preferably provide my pull socket with 90 two insulating members 7 and 8, usually formed of porcelain brought face to face and hollowed out to form the chamber 9 within which I mount my switch mechanism.

The meeting surfaces of the insulating members 7 and 8 are provided with concave recesses 10, 10 to form bearings for my axle or arbor 11, Fig. 6. This axle or arbor may be formed in any suitable manner, but preferably, for the sake 95 of economy of manufacture, I form it of a blank, Fig. 5, having the protruding members 12 and 13. When bent to form the axle 11, the member 12 becomes the pin or pawl 12, and the member 13 becomes the chain holder 13. This chain holder is provided with two tines 14, 14, one of them 100 being preferably, though not necessarily,

105

provided with a spring 15. In positioning the end 16 of the pull chain 17 within the slot 18 formed between the tines 14, 14, the spring 15 is bent down, so as to permit the chain to become seated and held within the slot 18. The spring 15 will then spring back to its original position and act as a spring catch to prevent the accidental disengagement of the pull chain 17 from the chain holder 13.

On this axle or arbor 11 is mounted the fiber or other insulating cam member 19, having the cam surfaces 20, 20 and 21, 21. On one side of the cam member 19 I mount a metallic conducting member 22 having bearing surfaces 23, 23 which fit over the cam surfaces 21, 21, as shown in Figs. 4 and 3. This makes every other cam surface a conductor. On the side opposite from the member 22, I provide the fiber or insulating cam member 19 with holes 24, 24 to cooperate with the fingers 25, 25 upon the ratchet 26 so that this ratchet 26 is secured to and moves with the insulating fiber cam member 19. The ends of the ratchet are cut and bent up as shown at 27, 27 to form teeth which contact with the pin or pawl 12 upon the axle or arbor 11.

Mounted in the path of the rotating cam member 19 are the two spring contact members 28 and 29. The contact 28 is secured by the screw 30, which in turn is secured to the plate 31. On this plate 31 is mounted one of the binding screws 32.

The spring contact 29 is one end of the center contact 33 of the pull socket. This center contact is provided at the end opposite the spring contact 29 with a toe 34, which hooks into a hole 35 in the insulating member 8.

The spiral spring 36 is coiled around the axle or arbor 11, one end 37 being mounted to cooperate with the chain holder 13, while the other end 38 is bent to form a hook to be seated in the recess or hole 39 in the porcelain or insulating member 8.

In positioning the parts the pull chain 17 is threaded through the eyelet or horn 40 and the end 16 secured to the chain holder 13, and in the manner previously described. The end 38 of the coil spring is then caused to assume the position shown in Fig. 8. By bringing the insulating members or porcelains 8 and 7 together, the spring 36 is wound up or put under tension automatically without any further manipulation by the assembler. In this position of the parts, the stop 41 on the pull chain 17 is brought into engagement with the narrow portion or neck of the horn 40, so that the chain cannot be further retrieved.

The two insulating members 8 and 7 are secured together by the securing screws 42 and 43, the latter cooperating with a nut 44 mounted in the slot 45 in the porcelain 7, see Fig. 7. The securing screw 42 screws

into the plate 46, which also acts as a nut. To this plate is also secured one of the binding posts 47.

It will be noted that the securing screws 42 and 43 are entirely encased in the porcelains or insulating members 7 and 8 and are removed and insulated from the chamber 9, within which the switch mechanism is mounted. This insures the pull socket from being short circuited. Should any foreign substance work into the chamber 9, which would short circuit an ordinary pull socket, in my pull socket it will only cause the lamp to burn, when the switch is in the off position, giving visible notice that it is out of order.

In Fig. 9 I have shown a modification in which, instead of the double break switch of the other figures, I use a semi-double break switch in which the fiber or insulating cam 48 is provided with an enclosing metal member 49 which covers three of the four faces of the cam, leaving the face 50 uncovered.

Mounted in the path of the cam are the spring contact members 51 and 52. The contact 51 is integral with the center contact 53 of the socket; the other spring contact 52 is held by the screw 70. In rotating the axle 11, on which this particular form of cam is mounted, the current will be broken when the parts are in the position shown in Fig. 9. As the end of the contact 51 jumps from the top 54 of one cam to the bottom 55 of the next succeeding cam, there will be a momentary flash, which will be duplicated, when the end of the contact 52 jumps from the point 56 to the point 57 of the succeeding cam. That is, the flash is divided between these two points and becomes in effect a double break or semi-double break switch having the well-known advantages of such a switch.

In Fig. 10 I have shown a further modification in which I employ a single-break switch. In this form the axle or arbor 11 has mounted upon it the rotating insulating or fiber cam 58, which has the cam surfaces 59, 60, 61 and 62, which cooperate with the spring contact member 63. Fitting on the cam is a metal contact member 64, which covers one side of the cam 58 and the cam surfaces 59, 60 and 61, leaving the cam surface 62 uncovered. A spring contact member 65 bears on the side of the member 64 and is always in electrical contact with it. By rotating the axle or arbor 11, the cam 58, with its metallic plate 64, is caused to rotate and will make electrical connection between the contacts, except when the parts are in the position shown in Fig. 10, when the current is broken.

In some cases, I may use a single piece porcelain, such as 66, Fig. 11. I may employ an interposed piece of fiber 67 between

the screw shell contact 4 and the single piece porcelain. The central chamber 68 contains the switch mechanism which is entirely separated and insulated from the securing 5 screws 42, 43. In this form of my invention the porcelain 66 is provided with a longitudinally extending slot for the reception of the axle or arbor 11.

The horn as shown in Fig. 1, is provided 10 with two bells or flared portions, one opening on the exterior of the pull socket and the other extending into the chamber 9 within the insulating members 7 and 8. This eyelet or horn 40 is secured primarily simply by 15 friction within the opening 68 within the porcelain.

In assembling the parts in the ordinary form of pull socket, the eyelet or horn becomes readily detached and misplaced, particularly when the cap and shell are removed to permit wiring of the pull socket. In my invention, on the contrary, even should the cap and the shell be removed for any reason, the eyelet or horn 40 will be retained in its proper location and position by the pull chain 17. That is, the stop which is preferably an enlarged ball 41, will engage in the throat of the eyelet or horn 40 and will tend to hold it in its position by means of the coiled spring 36, forcing the chain holder 13 into the position shown in Fig. 1. It will, therefore, be seen that my horn is held in position not only by friction but also by the pull chain 17.

It is quite common in the trade to ship pull sockets without the caps 2, the caps being afterwards added. In wiring all the pull sockets on the market, it is necessary to remove the porcelains, inclosing the switch 40 mechanism, from the metal shell 3 and its

fiber insulating shell 6. This requires extra time and manipulation to get the parts back after they are wired with the eyelet or horn placed in its proper position. In my invention, the binding posts 32 and 47 45 lie adjacent to the exposed surface of the insulating or porcelain member 7, so that it is not necessary to remove the pull socket from its enclosed shell 3 and insulating fiber 6, thereby avoiding the delay and the labor 50 and the expense of re-positioning the parts as above explained.

Having thus described this invention in connection with illustrative embodiments thereof, to the details of which I do not desire to be limited, what is claimed as new and what is desired to secure by Letters Patent is set forth in the appended claims. 55

What I claim is:—

1. A new article of manufacture comprising an axle adapted to be used in a pull socket switch, said axle being provided with a pin, a chain holder having two tines with a spring on one of the tines partly closing the opening between the tines and adapted to yieldingly hold the end of the chain from accidentally becoming disengaged from the chain holder. 60
2. In a pull socket the combination of a plurality of insulating members, a switch mechanism including an actuating chain and a spring, and means to automatically put the spring under tension and retract the end of the chain as the two insulating members are brought together and secured. 65
